CULINARY SCRAPER

Helmut Brugman, Indianapolis, Ind., assignor of
one-half to Hedwig Brueggeman, Coatesville,
Ind.

Application September 11, 1940, Serial No. 356,389

2 Claims. (Cl. 15—236)

This invention relates to a scraper for scraping sauce pans and other kitchen articles, the general object of the invention being to provide a handle having a metal blade attached thereto with a scraper blade made of Celluloid or the like with means for detachably connecting the scraper blade to the metal blade so that the scraper blade can be removed whenever desired so that it can be cleaned or another blade substituted for it.

This invention also consists in certain other features of construction and in the combination and arrangement of the several parts to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is an elevational view of the device.

Figure 2 is a section on the line 2—2 of Figure 1.

Figure 3 is a section on the line 3—3 of Figure 1.

Figure 4 is a section on the line 4—4 of Figure 1.

Figures 5 and 6 are views of different types of Celluloid blades.

In these views the numeral 1 indicates a handle and the numeral 2 indicates a metal plate having a shank 3 extending from one edge thereof of which is fitted into the handle, these parts forming a permanent portion of the device. The scraper blade proper is shown at 6 and is preferably formed of Celluloid and a smaller plate-like member 7 of Celluloid or the like is fastened at three of its edges to a portion of the blade or plate 6 adjacent the rear edge thereof with the other edge of the plate 7 free of the plate 6 so that the plate 7 forms a pocket for receiving the plate 2 which is inserted through the top of the pocket formed by the spaced rear edges of the parts 6 and 7. Snap fastener parts 8 are carried by the rear edge of the blade 6 and complementary snap fastener parts 9 are carried by the rear edge of the plate 7 so that after the plate 2 has been inserted in the pocket by fastening the parts 8 and 9 together the pocket is closed to hold the blade 6 in place. However, by removing the snap fastener parts from each other the pocket is open so that the blade 6 can be removed from the plate 2 and cleaned or repaired or another blade with a pocket can be substituted for the one removed. The blade can be of any suitable shape such as that shown in Figure 1 with the scraping edges having the corners rounded or it may be formed

as shown at 6' in Figure 5 which has the scraping end of the blade 6' rounded and tapered or it may be formed as shown at 6'' in Figure 6 to suit other types of utensils to be scraped. In every case, however, a pocket is formed by a second plate of Celluloid for receiving the metal plate 2 of the handle.

Thus it will be seen that I have provided a scraping blade of Celluloid or the like to be removably connected to a metal plate carried by a handle so that other blades can be substituted for the first blade and the blades removed for cleaning or repair purposes.

It is thought from the foregoing description that the advantages and novel features of the invention will be readily apparent.

It is to be understood that changes may be made in the construction and in the combination and arrangement of the several parts provided that such changes fall within the scope of the appended claims.

Having described the invention, what is claimed as new is:

1. A scraping device of the class described comprising a handle, a flat metal plate having a shank extending from one side edge thereof, the shank fitting in one end of the handle, a scraper blade having a straight rear edge, a small plate of flexible material having one side edge and its end edges fastened to one face of the blade with the other side edge of the small plate being flush with the rear edge of the blade, said small plate forming a pocket for receiving the metal plate and means for detachably connecting together the rear edge portions of the blade and small plate to hold the metal plate in the pocket.

2. A scraping device of the class described comprising a handle, a flat metal plate having a shank extending from one side edge thereof, the shank fitting in one end of the handle, a scraper blade having a straight rear edge, a small plate of flexible material having one side edge and its end edges fastened to one face of the blade with the other side edge of the small plate being flush with the rear edge of the blade, said small plate forming a pocket for receiving the metal plate and means for detachably connecting together the rear edge portions of the blade and small plate to hold the metal plate in the pocket, such fastening including snap fastener parts connected with the rear edge portion of the blade and complementary snap fastener parts connected with the rear edge portion of the small plate, such fastening means being located outwardly from the center of the pocket to permit the passage of the shank when the fastening means are in holding position.

HELMUT BRUGMAN.
